STOKER

Otto N. Moore and Robert P. Moore, Indianapolis,
Ind.

Application September 21, 1934, Serial No. 744,916

2 Claims. (Cl. 110—45)

Our invention relates to coal stokers, and it is our primary object to produce a stoker in which the regulation of the coal feed is secured by an extremely simple and effective mechanism. 5 Other objects of our invention include the provision of means for preventing in the air-supply passages any accumulation of riddlings or small coal particles which find their way through the tuyères of the fire-pot, and the provision of 10 means for preventing any flow of gases rearwardly from the fire-pot through the coal-feed passage and coal-hopper.

The accompanying drawings illustrate our invention: Figs. 1 and 2 are perspective views of 15 the complete stoker assembly; Fig. 3 is a vertical section through the furnace, hopper, and stoker assembly, with the blower in elevation; Fig. 4 is a perspective view of the fire-pot and its associated base with a portion of the fire-pot 20 wall broken away; and Fig. 5 is a fragmental vertical section on the line 5—5 of Fig. 3.

The stoker includes a coal-hopper 10 supported upon a suitable base 11 which also serves as a support for an electric motor 12 and a 25 blower 13. Near its bottom, the hopper 10 has a coal-discharge opening communicating with a circular coal-feed conduit 15 through which coal is fed to the fire-pot, the movement of coal being accomplished by means of a helical feed-screw 16 which is disposed within the conduit 15 and which extends rearwardly across the bottom of the coal hopper. The feed screw 16 is connected by any suitable power-transmission mechanism with the motor 12 to be driven there-by at substantially constant speed.

The fire-pot 20 to which coal is fed through the conduit 15 is conveniently of an inverted frusto-conical shape supported upon a hollow base 21 of a generally semi-circular shape. The 40 walls of the fire-pot 20 are hollow and communicate with the interior of the base 21. The inner surface of the fire pot is provided with tuyères 22 through which passes the air necessary to support combustion. At its lower end the interior of the fire pot 20 communicates 45 through an elbow 23 with the forward end of the conduit 15.

The plane vertical face of the base 21 is disposed toward the coal hopper and is provided 50 with a centrally located opening 24 for the reception of the forward end of the conduit 15. In addition, this vertical face of the base is provided near one lower corner with a clean-out opening 25 and, near the opposite lower corner 55 with an air-admission opening 26 to which air

is supplied from the blower 13 through a conduit 27 that extends through the hopper-base 11 and that is provided with a damper 27'.

The helical flight or rib of the feed-screw 16 is interrupted, preferably at or near the discharge opening of the coal hopper 10, and at this point of interruption we provide a transversely movable feed-regulating member. Conveniently, the feed-regulating member or valve 30 is vertically slidable in a suitable guide 31, its position being controlled by a suitable operating member 32. At its lower end, the valve 30 is provided with an upwardly extending slot embracing the shaft 16' of the feed screw 16, as is clear from Fig. 5 so that, except for such slot, the valve 30 can be operated to close the discharge opening of the hopper 10.

We have found it convenient to interrupt the helical rib of the feed screw 16 at several points within the hopper 10, as indicated by the numeral 34 in Fig. 3. Further, instead of sloping the side walls of the hopper 10 to a point closely adjacent the feed screw, we prefer to have such walls extend downward vertically to meet the plane horizontal base 10' of the hopper at points spaced a considerable distance from the feed screw 16. We find that this arrangement prevents the tendency of the coal to arch over the feed screw.

At some point in its length, preferably near the fire pot 20, the coal-feed conduit 15 is provided in its upper surface with an opening communicating with a pipe 40 which extends vertically beside the fire pot into the combustion chamber thereabove. The upper end of this pipe will be subject to the partial vacuum created by the normal up-flow of gases through the combustion chamber. This arrangement prevents gases from feeding backwards through the conduit 15 from the fire pot to the coal hopper, as any gases entering the conduit 15 from the fire-pot will be discharged upwardly through the pipe 40.

The clean-out opening 25 in the base 21 of the fire pot is preferably provided with an outward extension 25' (see Fig. 4) which communicates with a pipe 42 extending vertically beside the fire pot 20 and discharging within the furnace above the fire pot. Air from the blower 13 discharging tangentially into the semi-circular base 21 of the fire pot will tend to flow around the curved wall thereof and to pick up from the floor of the base any fine particles of coal or ash which may happen to pass through the tuyères 22. By the action of centrifugal force resulting

from the circular motion of air within the base 21, these fine particles will be carried toward the outside, and will pass through the opening 25' into the pipe 42, to be discharged within the furnace.

The purpose of the gate valve 30 is to permit control of the quantity of coal fed relative to the amount of air supplied to the fire without the necessity for varying the relative speeds of the 10 feed screw 16 and the blower 13, which may therefore be driven at constant relative speed. The valve member 30, controlling as it does the effective size of the opening through which coal passes from the hopper 10, regulates the amount 15 of coal which is fed at each revolution of the feed screw.

Our stoker is installed in association with a furnace as illustrated in Fig. 3. The fire-pot 20 is located within the furnace and the coal-hopper 10 and its associated parts are located near 20 but outside the furnace, the coal and air conduits 15 and 27 extending through the furnace casing. The two pipes 40 and 42 extend upwardly beside the fire-pot and are located wholly 25 within the furnace casing.

In operation, the hopper 10 is filled with coal which is fed to the fire pot by operation of the feed-screw 16. The feed-screw, being driven from the blower-motor 12 operates whenever the 30 blower operates, the motor usually being under

the control of some automatic temperature responsive mechanism. The ratio between the rate of coal-supply and the rate of air supply may be varied to suit conditions by adjustment of the valve 30 in the coal-supply conduit 15 while the feed screw 16 and blower 13 continue to operate at constant relative speed.

We claim as our invention:—

1. In a stoker, a fire-pot having hollow walls provided with inwardly opening tuyères, a hollow base supporting said fire-pot, the interior of said base communicating with the interior of said walls, said base having a generally vertical curved wall, means for discharging air into said base near the bottom thereof and tangentially of said curved wall, said base being provided with an opening positioned to receive air deflected by said wall, and a pipe communicating with the interior of said base through such opening, said pipe extending upwardly to a point 15 above and adjacent said fire-pot.

2. In a stoker, a fire-pot having hollow walls provided with tuyères through which air is discharged into the fire, a chamber below said fire-pot and communicating with the space within said hollow walls, means for blowing air into said chamber and said hollow walls so that it is discharged through said tuyères.
